Primary Examiner — Mehri F Bajoul(74) *Attorney, Agent, or Firm* — Justin Lampel(57) **CLAIM**

The ornamental design for an electronic story book as shown and described.

DESCRIPTION

FIG. 1 is a perspective view of an electronic story book showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of an electronic story book in a use status; and,

FIG. 10 is an enlarged view of area 10 shown in FIG. 1. The dash-dot-dash broken lines represent the bounds of the magnified portions and form no part of the claim.
